(57) **CLAIM**

The ornamental design for a trash can as shown and described.

DESCRIPTION

FIG. 1 is a perspective view of a trash can showing my new design;

FIG. 2 is a front view thereof; the back, left and right views not shown as they are identical;

FIG. 3 is a top plan view thereof; and,

FIG. 4 is a bottom plan view thereof.

The broken lines depict portions of the trash can and form no part of the claimed design.

1 Claim, 4 Drawing Sheets(56)
